UNITED STATES PATENT OFFICE.

HARRY D. PURSELL, OF WASHINGTON COURT-HOUSE, OHIO.

AWNNG FOR VEHICLE-TOPS.

SPECIFICATION forming part of Letters Patent No. 761,321, dated May 31, 1904.

Application filed February 27, 1904. Serial No. 195,689. (No model.)

To all whom it may concern:

Be it known that I, HARRY D. PURSELL, a citizen of the United States, residing at Washington Court-House, in the county of Fayette and 5 State of Ohio, have invented a certain new and useful Improvement in Awnings for Vehicle-Tops, of which the following is a specification.

My invention relates to vehicle-top awnings; and the objects of my invention are to provide a detachable awning for vehicle-tops of superior construction and arrangement of parts, to so construct said awning as to permit of the same being folded in a compact 15 form when not in use and to admit of its being readily and securely attached to and detached from the forward portion of a vehicle-top frame, and to produce other improvements, the details of which will be more fully 20 pointed out hereinafter. These objects I accomplish in the manner illustrated in the accompanying drawings, in which—

Figure 1 is a side elevation of a buggy-top, showing my improved awning attached thereto. Fig. 2 is a central transverse section of the awning and forward top bow, illustrating the manner of connecting the awning therewith. Fig. 3 is a transverse section on line $\alpha\alpha$ of Fig. 4; and Fig. 4 is an under side view in elevation 30 of the awning, showing the same unrolled or unfolded.

Similar numerals refer to similar parts throughout the several views.

In carrying out my invention I form my improved awning-body of an elongated flexible strip 1, preferably of waterproof material and of desirable width and suitable length. At intervals the body 1 is formed or provided with transverse casings 2, which extend from 40 the outer edge of the body to points beyond the center of the width thereof. While three of these casings are indicated in the drawings, it is obvious that any desired number may be employed. As shown in Fig. 4, one of the 45 casings 2 is arranged near each end of the body 1, and said body ends are preferably curved, as shown. Each of these curved ends has incased therein a suitable stiffening or reinforcing rod or material, such as is indicated

at 3, which stiffening-rod may consist of ratan 50 or other semiflexible material. Those portions of the body 1 which are on the outer sides of the outer casings 2 form awning end pieces or flaps, which I have indicated at 1^a, and to the outer portions of these end pieces 55 are secured suitable attaching devices, such as straps 4.

5 represents attaching and supporting devices, each of which comprises a rod of suitable length, one end portion of which is bent 60 upon itself, resulting in the formation of a comparatively small end loop 5^a; from which the bent member extends forward in contact with the body of the rod, from which it is bent upwardly and thence downwardly to form a 65 hook termination 5^b. In Fig. 4 of the drawings I have for the sake of clearness in illustration shown the central rod 5 turned at right angles from its normal or attaching position. The head portions of the rods 5 may 70 be sewed through the loops 5^a or at other suitable point to the body of the awning.

In attaching my improved awning to the buggy or other vehicle top, such as is indicated at 6, the upturned and inwardly-bent 75 hook portions 5^b of the rods 5 are brought into engagement, as shown, with the upwardly-projecting portion of the usual front valance 7 of the buggy-top, said hook portion being thus made to embrace the valance, while the 80 rearwardly-extending doubled portion of the rod extends inwardly beneath the forward top bow 8 in the manner illustrated in Fig. 2. As a preferable manner of producing this connection the awning-body is first held so 85 as to incline upward from the front of the vehicle-top to facilitate the engagement of the hooks with the valance-roll, said awning then being dropped or moved downward to the position shown in the drawings, in which positions, as will be understood, the awning assumes the downward incline, which corresponds to the incline of the under side of the forward bow 8. This attachment being effected as described, it is obvious that the depending side flaps 1^a may be further connected with the vehicle-top by securing the straps 90 or other fastening devices 4 to or about the 95

usual front top-props 9, these connections thus insuring the retention of the side flaps in their proper depending positions.

It is obvious that when not desired for use 5 in connection with a buggy-top the herein-described awning may be readily detached from said top and folded or rolled into compact form.

It will be understood that detachable awnings such as I have described can be utilized to advantage on buggy and other vehicle fronts for the purpose of shielding the occupants of the vehicle from sun, rain, or snow and that said device is of such construction 15 as to permit of its being manufactured and furnished at comparatively low cost.

Having now fully described my invention, what I claim, and desire to secure by Letters Patent, is—

20 1. In a detachable awning for vehicle-tops, the combination with a flexible awning-body, of hook projections connected at intervals therewith and projecting upwardly therefrom,

said hooks adapted to be engaged with the front valance and forward bow of a vehicle- 25 top.

2. In a detachable awning for vehicle-tops, the combination with a flexible awning-body 1, of transverse stiffening-rods secured at intervals thereto, the inner end portions of said 30 rods terminating in projecting hooks and the ends of said awning-body being provided with means for forming detachable connections with the sides of the vehicle-top.

3. In a detachable awning for vehicle-tops, 35 the combination with a flexible awning-body, of hooks connected with said awning-body at intervals for producing a detachable connection of the same with the forward portion of a vehicle-top, and means for engaging the 40 front bolts of the top-props.

HARRY D. PURSELL.
